(57) **CLAIM**

The ornamental design for a motor vehicle body, toy vehicle body replica, and/or other replica as shown and described.

DESCRIPTION

FIG. 1 is a front elevational view of a motor vehicle body, toy vehicle body replica, and/or other replica showing our new design;

FIG. 2 is a rear elevational view thereof;

FIG. 3 is a left side elevational view thereof;

FIG. 4 is a right side elevational view thereof;

FIG. 5 is a top plan view thereof.

FIG. 6 is a top, front, and left side perspective view thereof, and,

FIG. 7 is a top, rear, and left side perspective view thereof. The portions of the motor vehicle body and wheels shown in a de-emphasized faded out half-tone form surrounded by broken lines that represent and define some boundaries of the claimed design are for environmental and illustrative purposes that form no part of the claimed design.
